UNITED STATES PATENT OFFICE.

HENRY W. O'NEILL, OF BROOKLYN, NEW YORK, ASSIGNOR TO GRAY NATIONAL
TELAUTOGRAPH COMPANY, OF NEW YORK, N. Y., A CORPORATION OF VIR-
GINIA.

TELAUTOGRAPHIC APPARATUS.

1,127,083.

Specification of Letters Patent.

Patented Feb. 2, 1915.

Application filed April 22, 1912. Serial No. 692,225.

To all whom it may concern:

Be it known that I, HENRY W. O'NEILL, a citizen of the United States, residing at Brooklyn, county of Kings, and State of New York, have invented certain new and useful Improvements in Telautographic Apparatus, fully described and represented in the following specification and the accompanying drawings, forming a part of the

10 same.

This invention relates to improvements in telautographs of the variable-current strength type, that is to say, telautographs in which the movements of the receiving pen over its writing platen are controlled by variations in the strengths of the currents on the tracer lines connecting the transmitter and the receiver, which variations in current strength are in turn controlled by 15 the movements of the transmitting tracer over its writing field, so that the receiving pen moves in unison with, and reproduces the movements of, the transmitting tracer. The present invention has reference particularly to means controlled by the transmitting tracer for producing a vibratory condition of current on the tracer lines, which vibratory condition of current may be utilized either for the purpose of controlling the movements of the receiving pen to and from its writing platen or for vibrating the pen-moving parts at the receiver for the purpose of reducing frictional resistance to their movements.

35 In the accompanying drawings—Figure 1 is a diagrammatic view of a two-wire telautographic system comprising a transmitter and also a receiver connected therewith, the same being equipped with the improvements 40 constituting the present invention, which are shown therein as utilized for the purpose of moving the receiving pen to and from its writing platen or for pen "lifting"; and Fig. 2 is a similar view showing 45 the improvements utilized for the purpose of vibrating the pen-moving parts at the receiver.

Generally considered, the telautographic systems illustrated in Figs. 1 and 2 are of well-known form, so that, except for the features constituting the present invention, only a brief description thereof will be necessary.

Each transmitter comprises a pair of 50 rheostats 1, 2, included in a normally open

current-supplying circuit provided with a suitable source of electric energy, as, for example, a motor generator 3, the negative pole of which is grounded at 4, this local circuit being controlled by a master switch mechanism, designated 5 as a whole, controlling contacts 6, 7, 8, which, in the position in which they are shown, engage, respectively, stationary contacts 9, 10, and 11, thus completing the local current-supplying circuit just referred to, and also the tracer line circuits connecting the transmitter with the receiver.

The current-supplying circuit just referred to, which is closed by the engagement of contact 6 with contact 9, consists of wire 12, from the positive pole of generator 3, contacts 9, 6, wires 13, 14, wire 15 to rheostat 1, and wires 16, 17, 18 to rheostat 2, and wires 19, 20, 21, from rheostat 1, to the negative pole of generator 3, and wires 22, 23, 24, 20 and 21, from left rheostat 2, to the negative pole of generator 3. The tracer line circuits just referred to, which are ordinarily referred to as right and left tracer lines, are traced as follows: For the right line, contact 25, arm 26, wires 27, 28, contacts 10, 7, wires 29, 30, right hand relay 31, wire 32, movable coil 33, and wires 34, 35, 36 to ground at 37 at the receiver. For the left hand tracer line, contact 40, arm 41, wires 42, 43, contacts 11, 8, wires 44, 45, left hand relay 46, wire 47 and coil 48, wires 49, 36, to ground at the receiver.

The arms 26, 41, just referred to, are connected by levers 51, 52 with pen arms 53, 54, respectively, in the conveying ends of which is suitably mounted the transmitting tracer 55, all in the well known manner. It will be understood, of course, that as the transmitting tracer 55 is moved laterally, or, in other words, over its writing platen, roller contacts 25, 40 will be moved lengthwise of the rheostats 1, 2, respectively, and as they are thus moved, currents, varying in strength in accordance with the direction and extent of movements of these roller contacts, will be shunted into the right and left tracer line circuits just described, and, further, that such currents of varying strength will cause the coils 33, 48 to move varying distances in the magnetic field provided for them by the magnet 60, which magnetic field is excited separately from the coils 33, 48, that is to say, from a local

source of energy, as, for example, a battery 61, through circuit connections which will presently be described. The coils 33, 48 are connected in the well known manner by means of brackets 62 and segments 63 with levers 64, the latter being pivotally connected by pen arms 65 which carry in their pivoted converging ends the receiving pen 66. Therefore, as the coils 33, 48 are thus moved rectilinearly in their magnetic field, in accordance with the variations in current strength on the two tracer lines, the receiving pen 66 will be correspondingly moved and thus reproduce, both in extent and direction, the movements of the transmitting tracer 55 laterally or over its writing field, all in the well known manner. Of course, it will be understood that these coils 33, 48 are moved in one direction by the currents traversing the tracer lines and that their movements thereby are opposed by springs, which, as the currents decrease in strength, move the coils in the opposite direction, in the usual manner. The circuit from battery 61, by means of which magnet 60 is excited, is controlled in its opening and closing by the left hand relay 46, the armature 70 of which carries a contact 71 which engages a stationary contact 72, when said left hand relay 46 is energized by current traversing the left tracer line, armature 70 in such case moving the spring contact 71 into engagement with stationary contact 72, and thus closing this local circuit through magnet 60. This local circuit through said magnet is traced as follows: wire 73 from the positive pole of battery 61, wires 74, 75, magnet 60, wires 76, 77, 78, contacts 71, 72, and wires 79, 50, and 36 to ground at 37. So long as the tracer line circuits between the transmitter and receiver are open, relay 46 being deenergized contact 71 will be out of engagement with contact 72, this local circuit then being open. As soon, however, as the tracer line circuits are closed, magnet 46 will be energized by the current traversing the left tracer line, and thus bring contact 71 into engagement with contact 72, thus closing this local circuit.

The apparatus as thus far described provides simply for the lateral movements of the receiving pen, or, in other words, its movements over its writing platen. Means are also usually provided, controlled from the transmitter, for effecting movements of the receiving pen to and from its writing platen, and also for vibrating the pen-moving parts at the receiver for the purpose of reducing frictional resistance to the movement of the receiving pen over its writing surface. In the present case means, controlled from the transmitting tracer, are provided for producing a vibratory condition in the current traversing the tracer

line, which may be utilized for either of these purposes. In Fig. 1 they are shown as utilized for the purpose of effecting the movements of the receiving pen to and from its writing platen, other means being provided in such case for vibrating the pen-moving parts of the receiver, while in Fig. 2 they are shown as utilized for the purpose of vibrating the pen-moving parts at the receiver, other means being provided for effecting the movements of the receiving pen to and from its writing platen. The vibrating means provided by the present invention will first be described in connection with Fig. 1, and then in connection with Fig. 2.

Referring now to the receiver of Fig. 1, it will be observed that it is provided with a pen rest 85 mounted on the armature of the pen-lifter magnet 86 in proximity to the pen-carrying armature 65, so that when said magnet 86 is energized, pen rest 85 engaging pen arms 65 will move and hold the receiving pen 66 away from its writing platen, while on the other hand when said magnet 86 is deenergized, its armature will withdraw pen rest 85 out of pen-supporting position, so that the receiving pen will be moved by its resiliency or otherwise toward and into contact with its writing platen or the record strip thereon. The construction and method of operation of pen-lifter magnet 86 are so well-known that detailed description thereof here is unnecessary. This magnet 86 is energized from battery 61 through a branch of the local circuit through which magnet 60 is energized, this branch circuit consisting of wire 87 from magnet 60, the windings of magnet 86, wire 88, contacts 89, 90 inclosed in a tube 91, and wires 92, 78, contacts 71, 72, and wires 79, 50, 36 to ground. Tube 91 is mounted on an armature-diaphragm 93 adapted to be vibrated by polarized relay 94, and one of the contacts 89, 90 loosely engages the other so that when diaphragm 93 is so vibrated, the engagement between the contacts 89, 90 will be practically ineffective for the purpose of closing the branch circuit just described through magnet 86, as said magnet will remain deenergized so long as the diaphragm 93 is not so vibrated, the engagement between the contacts 89, 90 will be effective for the purpose of closing such branch circuit, with the result that said pen-lifter magnet 86 will be energized. The construction of this relay and the method of operation of the diaphragm 93 and the loose contacts 89, 90, are so well known that further description thereof is unnecessary. One of the windings (95) of the polarized relay 94 is bridged by wires 96, 97 across the right and left tracer lines 30, 45, at points on the transmitter side of the relays 31, 46, a condenser 98 being included in the wire 97 be-

5 between the right tracer line wire 30 and the relay 94, for a purpose hereinafter described. The other winding (99) of relay 94 is included in a circuit controlling the operation of paper-shifter magnet 100, this circuit being a branch of the local circuit from battery 61 for energizing field magnet 60, and consisting of wires 101, 102, magnet 100, wires 103, winding 99 of relay 94, wires 104, 92, 78, contacts 71, 72, and wires 79, 50 10 36, to ground at 80.

10 The condition of contacts 89, 90, relatively to each other, upon which the energization and deenergization of the pen-lifter magnet 86, and, therefore, the movements of the receiving pen away from and toward its writing platen, depends, is controlled from the transmitter, and by the transmitting tracer itself, through connections with the 20 right and left tracer lines which will now be described.

15 Referring now to the transmitter, it will be observed that it is provided with a short-circuiting buzzer-group, comprising a magnet 110, which is included in a branch circuit from the positive pole of generator 3, consisting of wire 111, including a non-inductive resistance 112 and tapped from wire 16, wire 113, the winding of magnet 110, 20 wire 114, wires 115, 116, and wire 117, including another non-inductive resistance 118, to the negative pole of generator 3. In the raised position of the transmitting tracer, however, and, therefore, the raised position 30 of platen switch 120, a shunt is formed around the magnet 110, and said magnet thus rendered inoperative, said shunt circuit consisting of wire 121 from wire 111, platen contact 120, stationary contact 122, 40 and wire 123 connecting, by wires 116, 117, to the negative pole of generator 3. Therefore, while the transmitting tracer is raised away from its writing platen, there will be no operation of the buzzer magnet 110, and 45 no effect produced thereby, and the connections hereinafter described, on the current traversing the right and left tracer lines, the result being that the relatively loose contacts 89, 90 will remain in effective engagement to retain the local circuit through pen-lifter magnet 86, closed, pen rest 85 in such case being held by said magnet in its outer or pen supporting position so as to hold the receiving pen 66 away from its writing 50 platen, which is, of course, the position, at the time, of the transmitting tracer with relation to its platen. Upon the depression of the transmitting tracer, however, and, therefore, depression of the platen switch 60 120, this shunt circuit is broken at the contacts 120, 122, and current passes from generator 3 through the magnet 110 by wires 111, 113, 114, 115, 116, 117 to the negative pole of the generator. In this condition of 65 the platen switch, additional means are pro-

vided for automatically and intermittently short circuiting magnet 110, consisting of wires 125 connected with wire 111, wire 126, contact 127, and armature 128 of said magnet, this shunt circuit being closed, of course, 70 when, on the energization of magnet 110, armature 128 thereof is moved into engagement with contact 127, current then passing from wire 111 around said magnet until it becomes deenergized, when its armature 128 75 will be retracted by a spring 129, thus breaking this shunt circuit, and reestablishing the circuit through magnet 110, and so on, said magnet being alternately energized and deenergized, and therefore, alternately making 80 and breaking the shunt circuit, at the contacts 127, 128. Through these contacts 127, 128, magnet 110 which has high resistance and impedance, in turn controls the 85 charging and discharging, in series, of a pair of condensers 130, 131, the former connected by wire 132 with the right tracer line wire 28, beyond arm 26, and by a wire 133 with the wires 116, 117, of the circuits just described, while the latter is connected by wire 90 134 with left tracer line wire 42, beyond arm 41, and by a wire 135 with the wires 125, 126 of the circuits just described. The purpose of these condensers 130, 131 is to cause alternating current waves to traverse the main 95 tracer lines from the transmitter to the receiver, and, at the latter, to pass through the winding 95 of the polarized relay 94. For this reason impedance coils 136, 137 are provided at the transmitter between arms 26, 100 41, which effectively choke off these waves at the transmitter so that they cannot pass through the transmitter circuits but must traverse the main tracer lines, while at the receiver impedance means are also present, 105 consisting of the relays 31, 46, and coils 33, 48, which choke off these waves at the receiver so that they cannot pass to ground, but must pass over wires 96, 97, and through relay 94 and condenser 98, bridged by said 110 wires across the right and left tracer lines at the receiver. The presence of these impedances at the points indicated confines the 115 alternating currents to a metallic circuit of low inductance consisting simply of the tracer line wires and their closing contacts, the bridge 96, 97, at the receiver, and the relay 94 which is to be operated by these waves. Of course, any suitable impedance 120 means may be used in lieu of those shown and described, and, in this connection, it may be noted that no special impedance coils are provided, at the receiver, as in the transmitter because the relays 31, 46, which are present anyway, as local circuit closing 125 means in the receiver of certain types of telautographs, may, as they are here, be used as suitable impedance means, care being taken that they be suitably constructed to 130 perform their ordinary function, and also 135

this additional impeding function and that they bear such relation to each other as to present a balanced condition which will not disturb the synchronism or symmetry of the 5 waves traversing the circuit. The presence of the condenser 98 in the line 96, 97, bridging the right and left tracer lines at the receiver and through the winding 95 of relay 94, is to render said winding non-sensitive to 10 the direct currents traversing the right and left tracer lines, but sensitive to the alternating waves traversing said lines as the condensers 130, 131, alternately charge and discharge.

15 The operation of the condensers 130, 131, stated in detail is as follows: Assuming contacts 6, 7, 8 to be in engagement with contacts 9, 10, 11, and current therefore to be on the tracer lines, so long as the transmitting tracer 55 is raised away from its writing platen and platen switch 120 is in raised position, the condensers 130, 131 stand discharged over the line circuit loop and the shunt formed by contacts 120, 122, 20 and no vibrations traverse the tracer lines. Winding 95 of pen-lifter relay 94 and the diaphragm 91, with the contacts 89, 90, are therefore quiescent and the circuit through pen-lifter magnet 86 remains closed, attracting 25 its armature, which, through pen rest 85, holds receiving pen 66 away from its writing platen. The instant, however, switch contact 120 is depressed by the tracer or the hand of the operator, this shunt circuit is opened and direct current flows 30 from positive of generator 3 through wire 17, resistance unit 112, winding of buzzer 110, resistance unit 118, to negative. This circuit condition effects the automatic operation of the short circuiting buzzer, as 35 when the armature 128 reaches the forward position contact 127 closes and effects a short circuit on the buzzer winding, de-energizing the coil. The armature thus released returns to original position, by the 40 action of the retractile spring 129. At this instant, contact 127 being open: the positive side of the direct current source, through wire 16, resistance unit 112, wires 45 125, 135, reaches one plate of condenser 131, and gives it a positive charge; the negative side of current source through wire 117, resistance unit 118, wire 133, reaches one 50 plate of condenser 130 and gives it a negative charge. The opposite plate of condenser 131 being connected to left line wire 43 and the opposite plate of condenser 130 to right line wire 28, it results that when 55 the plates take charge as above, the plates connected to the line wires will assert themselves over the path having lowest impedance or effective resistance, this path being that circuit formed from condenser 131 over wire 43 and line wires 44, 45, to 60 the receiving instrument and thence over 65 wire 96, condenser 98, alternating current relay 94, wire 97, line wires 30, 29 and wire 28, to condenser 130. Thus a positive impulse has emerged from condenser 131 and traversed the circuit described, being attracted to the negative plate of condenser 130 which is connected to line wire 28. 70

Now assume that the buzzer armature has again been attracted to the forward position, contact 127 being closed at this instant. 75 The positively charged plate of condenser 131 will now emit an impulse over wires 135, 126, buzzer contact 127, 128, and wires 115, 116, 133, to the negatively charged plate of condenser 130. Again this oppositely directed current action is possible owing to 80 the opposite plates of each condenser being connected to the line wires as described above. For this impulse the line side of condenser 130 is positive and the impulse emitted traverses the line and alternating current relay circuits in the direction opposite to that described above for the instant of charge. The condensers are now empty having discharged in series one with the 85 other through the connecting wires; short circuiting buzzer contacts, line wires and alternating current relay circuit as described. 90

Now, inasmuch as the movement to and fro of the buzzer armature 128 is very rapid, it is obvious that the condensers 130, 131 are charged and discharged respectively in phase with the opening and closing of the 95 buzzer contacts. Thus owing to the circuit arrangement as shown, whereby the condensers act in series for either impulse, charging or discharging, it necessarily follows that the total number of coulombs going out over one wire must return over the 100 other wire. This identical current condition in each wire for all impulses, results in one wire exactly neutralizing the inductive effects of the other wire. As described, 105 these alternating currents affect the alternating current relay armature diaphragm 93 causing it to vibrate in phase with the alternations. This in turn causes contacts 89, 90, to vibrate one relatively to the other, thus opening the circuit through pen-lifter 110 magnet 86, as before described, receiving pen 66 then moving into contact with its writing platen. Assume the transmitter pencil to be now raised from the platen: 115 Contacts 120, 122 close and through wires 121 and 123 effect a short circuit on the winding of buzzer 110, bringing the buzzer to rest, when the condenser action ceases, diaphragm 93 becomes quiescent, the circuit through pen lifter magnet 86 is closed, and 120 pen rest 85 moves receiving pen 66 away from its writing platen, which is, of course, the position, at the time, of the transmitting tracer 55 with relation to its platen. In this 125 position it will be clearly seen that the con- 130

verter group establishes a balanced condition of capacity and resistance between the line wires and local circuits in the transmitter. To consider one phenomena of this converter arrangement, the voltage of the alternating currents will vary inversely as the resistance of the resistance units 112 and 118 and directly as the resistance and impedance or effective resistance of buzzer coil 110.

The action of the condensers being instantaneous they will charge at a higher voltage than would be found by applying "ohms law" to the resistance relation of the units and buzzer coil. This is accounted for by the time factor relation between the condensers 130, 131 and buzzer coil 110, the impedance of the coil 110 presenting, on the instant, a very high effective resistance.

The importance of the buzzer group and condenser arrangement which have been described will be apparent from the following brief résumé: In order to operate telautograph instruments of the "Two wire" type over circuits adjacent to telephone lines as through telephone cables or aerial lines, the telautograph circuit must necessarily be a symmetrical wave conductor, *i. e.* the inductance capacity and ohmic or effective resistance of the two wires forming the circuit must be identical. In the telautographic system described, this balance is effected by the impedance coils 136, 137 at the transmitter and the relays 31, 46, and pen moving coils 33, 48, at the receiver.

In addition to the above requirements it is further necessary that the alternating current waves transmitted must be symmetrical, *i. e.* for a positive impulse in one wire there must be a negative impulse of equal strength in the other wire, as when one current alternation produces the same number of coulombs in each wire outgoing on one wire and returning over the other.

As the twisting of the cable pair and transpositions in aerial wires give the same surface exposure for each wire relative to adjacent conductors, it follows that at any given instant the extraneous induction set up by a positive impulse in one wire is entirely neutralized by the negatively induced field of the other wire. Hence, adjacent circuits are not affected. In order that the total number of coulombs going out over one wire, for a given impulse, shall return over the other wire, it is necessary that these alternating current waves be generated or converted by such means as will be entirely independent of the ground connections at either end of the line. The arrangement of the converter group at the transmitter fulfills these requirements.

The means present in the apparatus shown in Fig. 1 for vibrating the pen-moving parts in the receiver are those described and

claimed in my application filed February 24, 1912, Serial Number 679,588, and is as follows: The means provided in the present example consists of a short circuiting buzzer, the magnet 140 of which is located in the receiving instrument and included in a branch of a local circuit, for exciting field magnet 60, consisting of wire 241 from said magnet, winding of buzzer magnet 140, wire 244, and thence by wires 77, 78, contacts 71, 72, and wires 79, 50, and 36, of the field magnet circuit, to the negative pole of battery 61. This branch circuit, with the field magnet circuit, is closed only when writing currents are on line from the distant station, when, by the energization of relay 46, contacts 71, 72 engage. A shunt, including armature 246 of magnet 140, contact 247, wire 248, is formed, in this branch circuit, around magnet 140. When, therefore, said magnet is energized and attracts its armature 246, such armature, by engagement with front contact 247 will short circuit magnet 140. The latter will then release its armature 246, thus breaking this shunt circuit and reestablishing the circuit through the magnet; and so on, so long as the local circuit through field magnet 60 is closed. The winding of the upper magnet coil 60 is in multiple with buzzer 140. It follows that this winding will also be short circuited by armature 246 when it engages front contact 247. Therefore, the magnetic field in which the coils 33, 48, are located will be maintained in a vibratory condition, thereby greatly reducing frictional resistance to their movement.

Turning now to the apparatus shown in Fig. 2, in which the short circuiting buzzer group of Fig. 1 is used for vibrating the pen-moving parts of the receiver, other means at the transmitter being provided for pen-lifting or controlling the movement of the receiving pen to and from its writing platen, it will be observed that the right and left hand tracer lines from the transmitter to the receiver are the same as in Fig. 1, except for omissions of wiring due to the omission of the right hand relay 31. Therefore, the same reference numerals have been employed in Fig. 2 as in Fig. 1, so far as the tracer lines are concerned, except for such omissions. Polarized relay 94, with its connections, as well as paper-shifting magnet 100, and local short-circuiting buzzer group 140, are also omitted. In the present case, the movement of the receiving pen to and from its writing platen is, as in Fig. 1, controlled by a pen-lifter magnet 86, but here the energization and de-energization of this magnet 86 are effected from the

transmitter by a third line or circuit controlled by the platen switch 120 and stationary contact 122. This circuit consists of wire 145, leading from wire 17 of the current-supplying circuit at the transmitter, resistance 146, wire 147, platen contact 120, stationary contact 122, wire 147, a stationary contact 148, movable contact 149, wires 150, 151, 152, pen-lifter magnet 86, wire 153, and wires 77, 78, contacts 71, 72, and wires 79, 80, 86, to ground at 87 at the receiver. Contact 149 moves with the contacts 6, 7, 8, heretofore described, and when these several contacts are in engagement with their respective stationary contacts, current traverses the right and left hand tracer lines to the receiver, and also, so long as contacts 120 and 122 are in engagement, the pen-lifter line or circuit just described. Pen-lifter magnet 86 is thus energized and moves its armature to such position that the pen rest 85 carried thereby will move and hold the receiving pen 66 away from its writing platen, which is the position of the transmitting tracer with relation to its writing platen. When, however, the transmitting tracer is lowered into engagement with its writing platen, and platen switch 120 is consequently depressed, this third line circuit will be broken at 120 and 122, magnet 86 thus becoming deenergized and its armature carrying the pen rest 85 away from pen supporting position, so that the receiving pen 66 will rest against its writing platen, and will remain in this position so long as the transmitting tracer occupies a like position with relation to its platen. In this case the short-circuiting buzzer group, including the condensers 130, 131, is not, as in the case of Fig. 1, thrown into and out of operation or otherwise controlled by the platen switch 120, but continues in operation, producing on the right and left tracer lines the alternating current waves before referred to, so long as current is on the tracer lines. Except for this disassociation of the short-circuiting buzzer-group from the contacts 120, 122, the construction and method of operation of the short-circuiting buzzer-group and condensers in Fig. 2 is the same as heretofore described in connection with Fig. 1, these alternating current waves, however, being utilized in the case of Fig. 2 for another purpose, namely, for vibrating the pen-moving parts at the receiver, which function, in the case of Fig. 1, was performed by the local short circuit-buzzer group 140 at the receiver. To provide for such vibration of the pen-moving parts of the receiver by means of these alternating current waves, the bridging of the right and left tracer lines at the receiver by means of the wires 96, 97, as in Fig. 1, is omitted, so that these vibrations instead of passing from one tracer line to the other, in

advance of the pen-moving coils 33, 48, pass from over the tracer lines through such coils, closing circuit at the common ground connection at the receiver.

What is claimed is:

1. In a telautographic instrument of the variable current strength type, the combination with the tracer lines connecting the transmitter and receiver, a source of direct current supply therefor, means, including a transmitting tracer, controlling the strength of the currents therefrom traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, and a short-circuiting buzzer group connected with said source of current supply and automatically controlling the alternate charging and discharging of said condensers, whereby alternating current waves are caused to traverse the tracer lines. 90

2. In a telautographic instrument of the variable current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group connected with said source of current supply and automatically controlling the alternate charging and discharging of said condensers, whereby alternating current waves are caused to traverse the tracer lines, and suitable impedance means for diverting said waves from said current controlling means. 10

3. In a telautographic instrument of the variable current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group connected with said source of current supply and automatically controlling the alternate charging and discharging of said condensers, whereby 12

alternating current waves are caused to traverse the tracer lines, and suitable impedance means for diverting said waves from said current controlling means and said pen-moving parts.

4. In a tautograph instrument of the variable current strength type, the combination with the tracer lines connecting the transmitter and receiver, a source of direct current supply therefor, means, including a transmitting tracer, controlling the strength of the currents therefrom traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group, including a magnet connected with the positive and negative of said source of current supply, for automatically controlling the alternate charging and discharging of said condensers, whereby alternating current waves are caused to traverse the tracer lines, and resistances interposed between the buzzer magnet and the positive and negative of the source of current supply.

30 5. In a telautographic instrument of the
variable current strength type, the combination
with the tracer lines connecting the
transmitter and receiver, a source of direct
current supply therefor, means, including a
35 transmitting tracer, controlling the strength
of the currents traversing the tracer lines,
and electro-magnetic pen-moving parts at
the receiver controlled by such currents,
of a pair of condensers connected with
40 said source of current supply and with
the tracer lines and arranged to alternately
charge and discharge in series, one being
positively and the other negatively charged,
a short-circuiting buzzer group, including a
45 magnet connected with the positive and negative
of said source of current supply, for automatic-
ally controlling the alternate charging
and discharging of said condensers, whereby
alternating current waves are caused to trav-
50 erse the tracer lines, suitable impedance
means for diverting said waves from said
current controlling means, and resistances
interposed between the buzzer magnet and
the positive and negative of the source of
55 current supply.

6. In a telautographic instrument of the variable current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said

source of current supply and with the tracer lines and arranged to alternately charge and discharge in series, one being positively and the other negatively charged, a short-circuiting buzzer group, including a magnet connected with the positive and negative of said source of current supply and automatically controlling the alternate charging and discharging of said condensers, whereby alternating current waves are caused to traverse the tracer lines, suitable impedance means for diverting said waves from said current controlling means and said pen-moving parts, and resistances interposed between the buzzer magnet and the positive and negative of the source of current supply.

7. In a telautographic instrument of the variable current strength type, the combination with the tracer lines connecting the transmitter and receiver, a source of direct current supply therefor, means, including a transmitting tracer, controlling the strength of the currents therefrom traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, 95 a short-circuiting buzzer group connected with said source of current supply and automatically controlling the alternate charging and discharging of said condensers, whereby alternating current waves are caused to 100 traverse the tracer lines, and manually operable means at the transmitter controlling the condition, as to activity, of said condensers.

8. In a telautographic instrument of the variable current strength type, the combination with the tracer lines connecting the transmitter and receiver, a source of direct current supply therefor, means, including a transmitting tracer, controlling the strength of the currents therefrom traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group connected with said source of current supply and automatically controlling the alternate charging and discharging of said condensers, whereby alternating current waves are caused to traverse the tracer lines, and tracer operable means at the transmitter controlling the condition, as to activity, of said condensers. 125

9. In a telautographic instrument of the variable current strength type, the combination with the tracer lines connecting the transmitter and receiver, a source of direct 130

- current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group connected with said source of current supply and automatically controlling the alternate charging and discharging of said condensers, whereby alternating current waves are caused to traverse the tracer lines, suitable impedance means for diverting said waves from said current controlling means, and manually operable means at the transmitter controlling the condition, as to activity, of said condensers.
10. In a telautographic instrument of the variable current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group connected with said source of current supply and automatically controlling the alternate charging and discharging of said condensers, whereby alternating current waves are caused to traverse the tracer lines, suitable impedance means for diverting said waves from said current controlling means and said pen-moving parts, and tracer operable means at the transmitter controlling the condition, as to activity, of said condensers.
15. 11. In a telautographic instrument of the variable current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group connected with said source of current supply and automatically controlling the alternate charging and discharging of said condensers, whereby alternating current waves are caused to traverse the tracer lines, suitable impedance means for diverting said waves from said current controlling means, and tracer operable means at the transmitter controlling the condition, as to activity, of said condensers.
20. 12. In a telautographic instrument of the variable current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group connected with said source of current supply and automatically controlling the alternate charging and discharging of said condensers, whereby alternating current waves are caused to traverse the tracer lines, suitable impedance means for diverting said waves from said current controlling means and said pen-moving parts, and tracer operable means at the transmitter controlling the condition, as to activity, of said condensers.
25. 13. In a telautographic instrument of the variable current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group, including a magnet connected with the positive and negative of said source of current supply and automatically controlling the alternate charging and discharging of said condensers, whereby alternating current waves are caused to traverse the tracer lines, suitable impedance means for diverting said waves from said current controlling means and said pen-moving parts, resistance interposed between the buzzer magnet and the positive and negative of the source of current supply, and manually operable means at the transmitter controlling the condition, as to activity, of said condensers, said condensers, buzzer group, impedance means and resistances being so arranged and proportioned relatively to each other and to the tracer lines as to provide in the latter a balanced condition of circuit whether the condensers be active or inactive.
30. 14. In a telautographic instrument of the variable current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group connected with said source of current supply and automatically controlling the alternate charging and discharging of said condensers, whereby alternating current waves are caused to traverse the tracer lines, suitable impedance means for diverting said waves from said current controlling means and said pen-moving parts, and tracer operable means at the transmitter controlling the condition, as to activity, of said condensers.

variable current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group, including a magnet connected with the positive and negative of said source of current supply and automatically controlling the alternate charging and discharging of said condensers, whereby alternating current waves are caused to traverse the tracer lines, suitable impedance means for diverting said waves from said current controlling means and said pen-moving parts, resistances interposed between the buzzer magnet and the positive and negative of the source of current supply, and tracer operable means at the transmitter controlling the condition, as to activity, of said condensers, and said condensers, buzzer group, impedance means and resistances being so arranged and proportioned relatively to each other and to the tracer lines as to provide in the latter a balanced condition of circuit whether the condensers be active or inactive.

15. In a telautographic instrument of the variable current strength type, the combination with the tracer lines connecting the transmitter and receiver, a source of direct current supply therefor, means, including a transmitting tracer, controlling the strength of the currents therefrom traversing the tracer lines, and electro-magnetic pen-moving parts at the receiver controlled by such currents, of a pair of condensers connected with said source of current supply and the the tracer lines and arranged to alternately charge and discharge in series, one being positively and the other negatively charged, a short-circuiting buzzer group connected with said source of current supply and automatically controlling the alternate charging and discharging of said condensers, whereby alternating current waves are caused to traverse the tracer lines, tracer operable means controlling the condition, as to activity, of said condensers, and electro-magnetic devices controlled in their operation by said waves and in turn controlling the movement of the receiving pen to and from its writing platen.

16. In a telautographic instrument of the variable current strength type, the combination with the tracer lines connecting the transmitter and receiver, a source of direct

current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group connected with said source of current supply and automatically controlling the alternate charging and discharging of said condensers, whereby alternating current waves are caused to traverse the tracer lines, suitable impedance means for diverting said waves from said current controlling means, tracer operable means controlling the condition, as to activity, of said condensers, and electro-magnetic devices controlled in their operation by said waves and in turn controlling the movement of the receiving pen to and from its writing platen.

17. In a telautographic instrument of the variab' current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short-circuiting buzzer group connected with said source of current supply and automatically controlling the alternate charging and discharging of said condensers, whereby alternating current waves are caused to traverse the tracer lines, suitable impedance means for diverting said waves from said current controlling means and said pen-moving parts, tracer operable means controlling the condition, as to activity, of said condensers, and electro-magnetic devices controlled in their operation by said waves and in turn controlling the movement of the receiving pen to and from its writing platen.

18. In a telautographic instrument of the variable current strength type, the combination with the tracer lines connecting the transmitter and receiver, a source of direct current supply therefor, means, including a transmitting tracer, controlling the strength of the currents therefrom traversing the tracer lines, and electro-magnetic pen-moving parts at the receiver controlled by such currents, of a pair of condensers connected with said source of current supply and with the tracer lines and arranged to alternately charge and discharge in se- 130

- ries, one being positively and the other negatively charged, a short-circuiting buzzer group connected with said source of current supply and automatically controlling the alternate charging and discharging of said condensers, whereby alternating current waves are caused to traverse the tracer lines, tracer operable means controlling the condition, as to activity, of said condensers, electro-magnetic devices controlling the movement of the receiving pen to and from its writing platen, a circuit therefor including a pair of relatively loose contacts, and a relay bridged with a condenser across the tracer lines at the receiver and affected by the alternating current waves traversing the tracer lines and in turn vibrating the relatively loose contacts so as to break the circuit of which they form a part.
19. In a telautographic instrument of the variable current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short circuiting buzzer group connected with said source of current supply and automatically controlling the alternate charging and discharging of said condensers, whereby alternating current waves are caused to traverse the tracer lines, suitable impedance means for diverting said waves from said current controlling means, tracer operable means controlling the condition, as to activity, of said condensers, electro-magnetic devices controlling the movement of the receiving pen to and from its writing platen, a circuit therefor, including a pair of relatively loose contacts, and a relay bridged with a condenser across the tracer lines at the receiver and affected by the alternating current waves traversing the tracer lines and in turn vibrating the relatively loose contacts so as to break the circuit of which they form a part.
20. In a telautographic instrument of the variable current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short circuiting buzzer group connected with said source of current supply and automatically controlling the alternate charging and discharging of said condensers, whereby alternating current waves are caused to traverse the tracer lines, suitable impedance means for diverting said waves from said current controlling means, tracer operable means controlling the condition, as to activity, of said condensers, electro-magnetic devices controlling the movement of the receiving pen to and from its writing platen, a circuit therefor, including a pair of relatively loose contacts, and a relay bridged with a condenser across the tracer lines at the receiver and affected by the alternating current traversing the tracer lines and in turn vibrating the relatively loose contacts so as to break the circuit of which they form a part.
21. In a telautographic instrument of the variable current strength type, the combination with the tracer lines connecting the transmitter and receiver, a source of direct current supply therefor, means, including a transmitting tracer, controlling the strength of the currents traversing the tracer lines, and electro-magnetic pen-moving parts at the receiver controlled by such currents, of a pair of condensers connected with said source of current supply and with the tracer lines and arranged to alternately charge and discharge in series, one being positively and the other negatively charged, a short circuiting buzzer group connected with said source of current supply and automatically controlling the alternate charging and discharging of said condensers, whereby alternating current waves are caused to traverse the tracer lines, suitable impedance means for diverting said waves from said current controlling means and said pen-moving parts, tracer operable means controlling the condition as to activity, of said condensers, and electro-magnetic devices controlled in their operation by said waves and in turn controlling the movement of the receiving pen to and from its writing platen, said condensers, buzzer group, impedance means, and resistances being so arranged and proportioned relatively to each other and to the tracer lines as to provide in the latter a balanced condition of circuit whether the condensers be active or inactive.
22. In a telautographic instrument of the variable current strength type, the combination with the tracer lines connecting the transmitter and receiver, a source of direct current supply therefor, means, including a transmitting tracer, controlling the strength of the currents traversing the tracer lines,

and electro-magnetic pen-moving parts at the receiver controlled by such currents, of a pair of condensers connected with said source of current supply and with the tracer lines and arranged to alternately charge and discharge in series, one being positively and the other negatively charged, a short circuiting buzzer group connected with said source of current supply and automatically controlling the alternate charging and discharging of said condensers, whereby alternating current waves are caused to traverse the tracer lines, suitable impedance means for diverting said waves from said current controlling means and said pen-moving parts, tracer operable means controlling the condition, as to activity, of said condensers, electro-magnetic devices controlling the movement of the receiving pen to and from the writing platen, a circuit therefor, in-

cluding a pair of relatively loose contacts, and a relay bridged with a condenser across the tracer lines at the receiver and affected by the alternating current waves traversing the tracer lines and in turn vibrating the relatively loose contacts so as to break the circuit of which they form a part, said condensers, buzzer group, impedance means, and resistances being so arranged and proportioned relatively to each other and to the tracer lines as to provide in the latter a balanced condition of circuit whether the condensers be active or inactive.

In testimony whereof, I have hereunto set my hand, in the presence of two subscribing witnesses.

HENRY W. O'NEILL.

Witnesses:

J. F. DONOVAN,
T. F. KEHOE.
